OR THE LIKE

Angelo Boudouris, 1206 Cherry St., Toledo, Ohio

Filed Apr. 7, 1960, Ser. No. 60,077

Term of patent 14 years

(Cl. D1—12)

FIG. 1.

FIG. 2.

FIG. 1 is a front view in perspective of a menu sign for drive-in restaurants or the like embodying my new design,

FIG. 2 is a rear view in perspective of the menu sign shown in FIG. 1, and

FIG. 3 is a view in cross section of part of the menu sign shown in FIGS. 1 and 2, taken along the line 3—3 of FIG. 1.

The dominant features of my design reside in the solid line portions of the drawing.

I claim:

The ornamental design for a menu sign for drive-in restaurants or the like, substantially as shown and described.
